UNITED STATES PATENT OFFICE.

ALLAN RAMSEY, OF CHICAGO, ILLINOIS.

CASTER.

1,367,922.

Specification of Letters Patent.

Patented Feb. 8, 1921.

Application filed October 11, 1920. Serial No. 416,207.

To all whom it may concern:

Be it known that I, ALLAN RAMSEY, a citizen of the United States of America, and a resident of Chicago, county of Cook, 5 State of Illinois, have invented certain new and useful Improvements in Casters, of which the following is a specification.

This invention relates to bearings, casters or shoes adapted for attachment to household furniture of various kinds such as chairs, tables, pianos, clocks and other devices intended to be set rigidly on the floor, shelf or other support. More specifically it pertains to that class of caster-like goods 10 which includes certain attachments known to the trade as "domes of silence", used to prevent wear and noise and to facilitate moving the article from place to place.

The main objects of this invention are to 20 provide an attachment such as referred to adapted for ready application to the furniture, and capable of quick adjustment to attain the necessary elevation of the foot or other part of the object to be supported 25 in order to secure a stable setting thereof and insure against wobbling; to provide such a device of ornamental character adapted for convenient manual setting at any intermediate stage of its range of adjustment 30 and without the use of any tools; and to provide simple and inexpensive means adapted to prevent accidental change of adjustment of the device.

An illustrative embodiment of this invention is shown in the accompanying drawings in which—

Figure 1 is a front elevation of a stool having adjustable sliding casters secured to its legs.

40 Fig. 2 is an enlarged view of one of the attachments and the adjacent part of the corresponding furniture leg.

Fig. 3 is a section on the line 3—3 of Fig. 2.

45 In the construction shown in the drawings the stool leg 1 is provided with sliding shoe or caster 2 which is held in place by the axially disposed screw 3.

The said caster comprises mainly a pair 50 of coaxially disposed overlapping members adapted to mutually interfit and screw one within the other telescopically, one of said members being secured to the object to be supported and the other being arranged to bear upon the floor. In this instance the inner member 4 is secured to the leg 1 and

the outer member or shoe proper 5 rests on the floor. Said members 4 and 5 are each cup-shaped, the inner member being inverted. Means 6 are provided for maintaining 60 the adjustment of said parts 4 and 5 relative to each other, said means being in the form of a compression spring of helical shape disposed co-axially with said members 4 and 5. The screw 3 fits in a central 65 perforation 7 in the member 4 and the head of the screw bears against the inner face of the bottom of said member 4.

The caster may be attached to the furniture as follows: The device 2 is first taken 70 apart and then the inner member 4 is secured in place by the fastening screw 3. The shoe member proper 5 is then applied with the spring 6 in place and screwed upon the member 4 as shown in Fig. 3. The elevation of the object 1 is adjusted by screwing the part 5 either forwardly or backwardly, as will be understood. The spring 75 6 by reason of its pressure serves to prevent any movement or vibration of the furniture 80 from turning the shoe cup 5 or loosening the same in any appreciable degree. Hence said member 5 is substantially fixed except when it is forcibly turned in assembling or adjusting the device. The member 5 is 85 formed to facilitate gripping with the hands, and for this purpose is roughened, corrugated, knurled or grooved as shown at 8 on Fig. 2. The only tool necessary for attaching the member 4 to the furniture, is a 90 screw-driver, and no tool is required for adjusting the member 5.

The members 4 and 5 are preferably made of metal. They may be formed by casting or they may be forged or pressed. Screw 95 threads are then formed thereon as shown at 9 and 10. The bottom or bearing face 11 of the shoe proper 5 is convex-shaped or the edges at least are rounded and smooth to facilitate sliding on the floor. Said face 100 11 may to advantage be highly polished.

Although but one specific embodiment of this invention is herein shown and described, it is to be understood that some of the details of the construction shown may be altered or omitted without departing from the spirit of this invention as defined by the following claims.

I claim:

1. An adjustable caster of extensible character comprising a pair of members disposed in telescopic relation to each other and hav-

ing threaded mutual engagement, in combination with resilient means arranged to react forcibly between said members to prevent accidental relative turning thereof.

5 2. An adjustable caster comprising a pair of mutually inverted cup-shaped members adapted to fit adjustably one within the other, the bottom of one cup being axially perforated and provided with a screw for

engaging the object to be supported, said screw being disposed with its head against the inner side of said one cup and with its threaded shank projecting upward to engage said object.

Signed at Chicago this 8th day of October, 1920.

ALLAN RAMSEY.
